ACTUATING MECHANISM FOR SENSITIVE
HORIZON BARS

John S. Adkins, Dayton, Ohio

Application March 21, 1949, Serial No. 82,673

6 Claims. (Cl. 33—204)

(Granted under the act of March 3, 1883, as
amended April 30, 1928; 370 O. G. 757)

1

The invention described herein may be manufactured and used by or for the United States Government for governmental purposes without payment to me of any royalty thereon.

This invention relates to improvements in aircraft flight attitude indicating instruments and more particularly to actuating mechanisms for shifting the horizon indicating bars of vertical gyro indicators, having for an object the provision of improved actuating means for increasing the sensitivity of the horizon indicating bar of a vertical gyro indicator or artificial horizon.

Another object of this invention is the provision of improved horizon bar actuating means which permits maximum freedom of movement of the actuating gimbal means for the bar, and is extremely sensitive throughout the range of movement of the bar, particularly at or near the level or "zero" indicating position of the bar.

A further object is the provision of a horizon bar actuating mechanism which is extremely sensitive and accurate throughout the range of movement of the bar, particularly at or near the zero indicating position, having improved interengaging actuating means between the bar and the actuating gyroscope casing or rotor bearing member for positively coordinating the movement and position of the horizon indicating bar throughout the complete relative tilting movements of the actuating gyroscope casing and gimbal without obstructing or materially resisting its tilting movements.

Other objects and advantages of the invention will become apparent from the following descriptions, taken in connection with the accompanying drawings, in which like reference characters refer to like parts in the several figures.

Fig. 1 is a side elevation of an artificial horizon indicating gyroscopic instrument, incorporating my improved horizon bar actuating mechanism, parts of the casing and the supporting structure being broken away and shown in section.

Fig. 2 is a detailed perspective view of the horizon bar member and the cam and pin actuating means therefor, illustrating the parts somewhat diagrammatically, in their relative positions when the horizon bar is in its level or "zero" position.

Fig. 3 is a side elevation of the horizon indicating bar means and the cam and pin actuating means therefor, diagrammatically illustrating the relative position of the cam and pin when the horizon bar is shifted to one end of its range of movement by the pin, which is shown in dotted lines, when the cam has been rotated in the direction of the arrow to the position where the move-

2

ment of the bar by the pin is discontinued and the relative cooperative engagement between the bar member 14 and the periphery of the cam means is established, the dotted lines illustrating the position of the pin just as it disengages the horizon bar slotted structure, and the full lines illustrating a further relative rotative movement of the cam member and pin while the bar member is in cooperative controlled engagement with the periphery of the cam member and is positioned by the cam member.

Fig. 4 is a view similar to Fig. 3, but showing the horizon indicating bar and the actuating cam member in full lines, after the cam and pin have been rotated relative to the case, throughout a sufficient angular distance in the direction of the arrow to shift the horizon bar to the other end of its range of movement, the full lines showing the bar while under the control of the periphery 20 of the cam while the dotted lines show the pin shifted to the position where the bar actuation by the pin begins and the actuation of the bar member by the cam is interrupted.

Fig. 5 is a detail vertical sectional view taken approximately on the plane indicated by the line 5, 5 in Fig. 2.

Referring more particularly to Fig. 1 of the drawings, an artificial horizon is shown illustrated, the reference numeral 1 denoting an outer casing having a fore-and-aft axis as indicated at 2. The casing 1 comprises an airtight container of conventional design having a transparent front window 3 through which the horizon indicating bar member 4 is observed, bank angle indicating indicia (not shown), being inscribed on the flange 5, an adjustable fore-and-aft or horizon reference member for the aircraft, being indicated at 6, preferably in the form of a miniature airplane which is adjustable vertically with respect to the horizontal axis of the casing 1 and the mid-position of the horizon bar 4a by an adjusting knob 7.

The stabilizing means or gyroscope device as shown comprises a gimbal ring 8, pivoted on suitable fore-and-aft antifriction trunnions (not shown), but of conventional construction, and arranged to tilt about the fore-and-aft axis 2, the gimbal ring 8, as shown in Fig. 1 is broken away, but extends forwardly at opposite sides of the rotor casing or bearing member 9 and in turn pivotally supports the rotor bearing member or casing 9 on a transverse axis or pivots 10 in the conventional manner so that the rotor bearing member may tilt about the pivotal axis 10 which intersects the fore-and-aft axis 2 and is trans-

verse to the fore-and-aft axis 2. The rotor (not shown) is spun within the casing 9 on a normally vertical axis 10 by any suitable conventional means such as by an electric motor, or by the usual air jets. The rotor bearing member of case 9 is pendulous, or a suitable erecting means may be provided to erect the gyroscope rotor spin axis to the true vertical in a manner well known in the prior art, so that the normal vertical axis 10 corresponds to the true vertical at all times.

A spherically curved indicator plate 12 is provided, secured to an arm (not shown) projecting from the front end of the gimbal ring 8 the plate having an index pointer or indicator 12a projecting upwardly from its top edge to cooperate with the scale on the flange 5, to indicate the degree of lateral tilt or bank of the casing 1 and, of course, the bank angle of the aircraft on which the horizon is mounted relative to the vertical position of the rotor bearing casing or rotor spin axis 9, a supporting part of the aircraft being diagrammatically indicated at 13.

The horizon bar structure, as best seen in Fig. 2, comprises a bail-like member having laterally spaced side arms or connecting parts 14 and 15 extending rearwardly from the indicating bar member 4a proper, the extremities of the side arms 14 and 15 being pivoted on the gimbal ring 8 rearwardly of the axis 10, and parallel to the axis 10. The pivots for the bar are located in a plane passing through the fore-and-aft axis 2 so that when the horizon bar 4 is in the horizontal position its center will lie in the last mentioned plane. The connecting member or arm 14 is laterally offset, as indicated at 16, and is also apertured intermediate the arm 4a and the pivot point for the arm to leave an enlarged opening 17 having parallel guide edges lying at opposite sides of a plane passing through the pivots for the arms 14 and 15 and through the indicating bar member 4a. In other words the portion 14 of the bar member 4 is provided with parallel side bars projecting forwardly at opposite sides of the pivotal axis for the bar, the adjacent edges of the parallel side bars being indicated at 18; 18, the remote ends of the bars converging together towards the horizon indicating bar 4a at their front ends.

Projecting radially forward from the pivotal axis of the horizon indicator bar member 4 is a slotted extension 19 having a short open ended slot 20 opening into the large opening 17, the axis of the slot 20, and of the extension 19, being disposed in parallel offset relation to the side bars or edges 18 and projects radially forward toward the horizon bar portion 4a. The horizon bar 4-4a is formed of thin, light material such as a thin sheet aluminum or brass stamping and it may be counterbalanced at its rear end in the conventional manner if desired.

Secured to the rotor bearing member 9, on the pivotal axis 10 thereof, is a somewhat triangular shaped actuating cam member, indicated generally at 21, having a peripheral channel or groove 22. The parallel spaced side bars or edges 18 are received in, and retained in, the channel 22 by the side flanges of the channel. The cam member 21 is formed with two arcuate surfaces 23-24, having different radii, their peripheries being located in the base of the channel 22. The radial distance between the center of the arcuate surface 23, is greater than the radius of the other surface, both surfaces having their centers located substantially at the rotary axis 10 of the cam member, the radius of the surface 23 is equal

to substantially the distance between the axis 10 and the side edge 18 which is at the greater distance from the axis 10 when the horizon bar is shifted to the end of its range of movement as shown in Fig. 3 or Fig. 4. The other or smaller radial distance from the axis 10 to the arcuate surface 24, is equal substantially to the distance from the other or closer straight edge 18 to the axis 10 under the same condition. The sum of the two radial distances just mentioned is slightly less than the distance between the two straight edges 18.

The cam 21 is formed with curved contiguous surfaces 25 connecting the two arcuate surfaces 23 and 24 at their ends, the greatest distance between these two curved connecting surfaces being somewhat less than the distance between the straight edges 18 so as to leave some "play" between the cam member 21 and the edges 18 throughout at least a greater portion of the range of swinging movement of the horizon bar indicator member 4a, particularly when the cam 21 is at or near the positions shown in Figs. 1 and 2.

Located in a plane bisecting the greater arcuate surface 23 and passing through the axis 10 in parallel relation to the axis 10 is an actuator pin or slide member 26, arranged to engage the sides of the open ended slot 20 when the cam 21 is in the positions shown in Figs. 1 and 2, and when the casing 1 and gimbal ring 8 are tilted in the vertical plane from the position shown, to displace the positions of the cam 21 and slide or pin 26, displacing the horizon indicator member 4a to the position shown in Fig. 3 or 4. After the cam 21 is relatively rotatably displaced to dispose the pin 26 in the position shown by the dotted pin 26 in Figs. 3 and 4, the pin by that time having swung the horizon bar to its extreme range of movement leaves the slot 20 as the arcuate surfaces 23 and 24 of the cam 21 engage the straight edges 18, this position being shown in Figs. 3 and 4 in full lines. Continued rotation of the case about the axis 10 (or relative rotation of the rotor bearing member 9 and the cam 21 thereto) will cause the larger arcuate surface 23 to engage the opposite straight edge portion 18, shifting the horizon bar 4a to the opposite end of its range of movement, of course, shifting the position of the entrance end of the slot 20 so that the pin 26 can now enter the slot, the actuation of the horizon bar being then caused by the movement of the pin 26 in the slot 20 instead of the movement of the cam 21. The position of the actuating pin 21 at a remote distance from the pivotal axis 10, so as to swing close to the pivotal axis for the horizon bar member 4 while the pin is in the slot 20 affords an extremely sensitive and positive adjustment of the horizon bar 4a throughout its complete range of movement, the degree of movement of the bar being somewhat exaggerated with respect to the degree of relative tilt of the rotor bearing member 9, particularly at and adjacent to the horizontal, or zero, or level position, accurately indicating the degree of tilt of the fore-and-aft axis 2 as indicated on the scale 12, throughout the entire range of movement of the horizon bar 4a, and also permits free relative rotative displacement of the rotor bearing member vertical axis 10 about either the fore-and-aft axis 2 or about the lateral axis 10.

In the operation, as the casing, or the fore-and-aft axis, tilts with respect to the rotor bearing member 9 from the position shown in Fig. 1, the pin 26 engages the slot 20 and swings the horizon bar 4a throughout its range of movement to the

position where the pin leaves the slot 20 and the periphery of the cam member 21 now engages the sides 18 of the open portion of the horizon bar lever arm 14 to retain the horizon bar 4a its maximum upper (or lower) indicating position, and relative rotation of the gimbal ring 8 and case 1 around the axis 10 causes the periphery of the cam member 21 to strike the opposite straight edge portion 18 and shift the horizon bar member 15-4a to the other extreme indicating position with respect to the scale 12, the arcuate surfaces 23, 24 retaining the lever arm 14 and its bar member 4a in this position during the relative rotation of the parts and until the pin 26 again enters the slot 20 as the arcuate surfaces 23, 24 move away from the straight edge portions 18. Continued rotation of the fore-and-aft axis 2 about the transverse axis 10 brings the cam member 21 again into the position shown in Fig. 1 where the pivots 10 and 15 and the slide member or pin 26 line up, with the bar 4a indicating the level position as shown.

Having shown and described a simple embodiment of my invention, it is understood that the invention is not limited to the exact details of construction disclosed herein and minor changes and modifications may be made without departing from the spirit of the invention as defined in the accompanying claims.

I claim:

1. In an artificial horizon for aircraft, a rotor and a rotor bearing member, a gimbal ring having a transverse axis upon which said bearing member is pivotally mounted, an outer casing having a fore-and-aft axis upon which the gimbal ring is pivoted, a horizon indicating bar member pivoted about a transverse axis on the rear portion of the gimbal ring, having a horizon indicating portion spaced remotely forward from the bar member pivot, having an intermediate connecting portion formed with spaced parallel side bar members extending forwardly from the bar member pivot at opposite sides thereof and formed with a short laterally offset portion projecting radially forward between the parallel side bar members, having a guide slot therein opening towards the indicating portion of the bar member with the side walls of the slot extending in parallel relation to the space parallel side bar members, horizon bar adjusting means comprising a cam and pin actuator fixed on the rotor bearing member to rotate therewith about the pivotal axis thereof, having a pin projection thereon disposed in actuating engagement with the short slot throughout a predetermined range of travel of the indicating bar member above, and below, the intermediate or zero indicating position thereof, and disengageable from the short slot upon continued rotation of the cam and pin actuator and movement of the indicator bar to the predetermined maximum range of travel thereof, said cam having a periphery engageable with the parallel side bar portions of the horizon indicating bar upon continued rotation of the cam and pin member, to determine the position of the bar member relative to the rotor bearing member while the pin is withdrawn from its engagement with the short slot by the continued rotation of the cam and pin actuator.

2. In an artificial horizon for aircraft, a rotor and a rotor bearing member, a gimbal ring having a transverse axis upon which said rotor bearing member is pivotally mounted, an outer casing having a fore-and-aft axis upon which the gimbal ring is pivoted, a horizon indicating bar member

pivoted about a transverse axis on the rear portion of the gimbal ring, having a horizon indicating portion spaced remotely from said bar member pivot and an intermediate connecting portion formed with an enlarged transverse opening extending therethrough, having a short camming slot extending from the opening toward the bar member pivot, horizon indicator bar member actuating means fixed on the rotor bearing member to rotate therewith relative to the casing about the pivotal axis of the rotor bearing member, engageable with the short camming slot throughout a predetermined indicating range of swinging movement of the horizon indicating member and a corresponding degree of rotative movement of the rotor bearing member about its pivot, and disengageable from the short slot and subsequently engageable with the edge of the said opening throughout the balance of the relative rotative movement of the rotor bearing member, to control the position of the horizon bar member and the position of the short slot relative to the pivotal axis of the gimbal ring throughout the range of relative rotative movement of the bearing member with respect to the gimbal ring.

3. In an artificial horizon for aircraft, a rotor and a rotor bearing member, a gimbal ring having a transverse axis with which said rotor bearing member is pivotally mounted, an outer casing having a fore-and-aft axis upon which the gimbal ring is pivoted, a horizon indicating bar member pivoted about a transverse axis on the rear portion of the gimbal ring, having a horizon indicating portion spaced remotely forward from the bar member pivot with an intermediate connecting portion formed with an enlarged transverse opening therethrough having spaced side edges extending in parallel planes at opposite sides of the bar member and transverse to the pivotal axis of the bar member, said horizon bar member connecting portion having a lateral offset portion formed with an open slot communicating with said opening and extending radially toward the bar member pivot in an offset plane parallel to the opposite edges of the enlarged opening, rotary bar actuating means fixedly carried by the rotor bearing member to rotate therewith, comprising a somewhat triangular shaped cam member having arcuate peripheries of predetermined different radii located at diametrically opposite sides of the pivotal axis of the rotor bearing member, the combined radii of the arcuate surfaces being equal to substantially the distance between the parallel edges of the opening with the greater radius equal to substantially the distance between the rotor bearing member pivot and the side of the said transverse opening most remote from the bearing member pivot when the horizon indicating bar member is rotated on its pivot to an extreme indicating position limit at the end of its range of movement, while the radius of the other arcuate surface is equal to the distance between the bearing member pivot and the opposite or nearest parallel side of the opening, said cam member being disposed within the opening in the bar member connecting portion in the path of movement of the bar members, to actuate the bar member, and a pin member projecting laterally from the cam member into the plane of movement of the laterally offset portion, to enter the open slot, engageable with the side walls of the slot, to actuate the horizon bar member while the arcuate surfaces of the cam member are out of engagement with the spaced parallel edges of the opening in the

intermediate connecting portion of the horizon bar member.

4. In an artificial horizon for aircraft, a rotor and a rotor bearing case, a gimbal ring having a transverse axis upon which said rotor bearing case is pivotally mounted, an outer casing having a fore-and-aft axis upon which the gimbal ring is pivoted, a horizon indicating bar member pivoted about a transverse axis on the rear portion of the gimbal ring, said bar member having an open ended short slot extending radially away from the rotor bearing case pivot in a transverse plane, formed with an enlarged opening disposed in communication with said short slot, having a pair of parallel side edges which are offset laterally from the short slot at opposite sides of the pivotal axis of the rotor bearing case, a horizon bar actuator member responsive to relative rotative movement of the rotor bearing case, having a slide operable in the slot to swing the horizon bar member through a predetermined exaggerated angle at a rate proportional to the rate at which the rotor bearing case tilts, said slide movable out of the slot to disengage the horizon bar member at angles of tilt thereof greater than said predetermined angle, and a disc-shaped actuator member upon which said slide is fixed, secured to the bearing case to rotate therewith about the bearing case pivot, having offset camming surfaces thereon movable into actuating engagement with the parallel side edges of the opening for holding the horizon bar member in its maximum shifted positions, and shifting the bar member relative to the rotor bearing case when the slide is disengaged from the slot and the rotor bearing case rotates about its pivot beyond a predetermined degree.

5. Apparatus as claimed in claim 4 in which the disc-shaped actuator member is formed with a peripheral groove to receive the parallel side

edges of the horizon bar member therein, and is formed with arcuate camming surfaces in the base of the peripheral groove which are engageable with the parallel side edges of the horizon bar member when the slide is disengaged from the slot, to hold the horizon bar member in a predetermined adjusted position, and position the entrance of the short slot for subsequent engagement with the slide incident to subsequent relative rotative movement between the gimbal ring and the rotor bearing case.

6. Apparatus as claimed in claim 5 in which the arcuate surfaces are disposed at opposite sides of the pivotal center of the rotor bearing case with their radial centers at the pivotal center, having radial distances from their pivotal centers to the arcuate surface equal substantially to the distance between the spaced parallel side edges, one of the radial distances being greater than the other, and equal respectively to the distance between the bearing case pivot and the parallel side edge of the opening through the horizon bar member when the bar member is shifted to its maximum deflected indicating position, with the slide disengaged from the slot.
